US00D800995S

(12) **United States Design Patent** (10) Patent No.: **US D800,995 S**
(45) Date of Patent: **** Oct. 31, 2017**

(54) **APPAREL WITH ANGLED STRETCH PANEL**(71) Applicant: **Kimberly-Clark Worldwide, Inc.**,
Neenah, WI (US)(72) Inventors: **Jeanne Marie Gatto**, Evanston, IL
(US); **Christina Mae Chingren Seward**, Blairsburg, IA (US)(73) Assignee: **Kimberly-Clark Worldwide, Inc.**,
Neenah, WI (US)(**) Term: **15 Years**(21) Appl. No.: **29/587,571**(22) Filed: **Dec. 14, 2016**

CLAIM

The ornamental design for apparel with angled stretch panel, as shown and described.

DESCRIPTION

The FIGURE is a rear view of an embodiment of apparel with an angled stretch panel according to the present design. In the FIGURE, the broken lines represent portions of the article that form no part of the claim. The claim extends to the broken lines at the bottom and sleeves of the article but does include the broken lines.

1 Claim, 1 Drawing Sheet See application file for complete search history.
